UNITED STATES PATENT OFFICE.

SIDNEY GRANT STUART, OF BOSTON, MASSACHUSETTS.

AUTOHARP.

SPECIFICATION forming part of Letters Patent No. 593,701, dated November 16, 1897.

Application filed September 21, 1894. Serial No. 523,682. (No model.)

To all whom it may concern:

Be it known that I, SIDNEY GRANT STUART, of Boston, county of Suffolk, State of Massachusetts, have invented an Improvement in 5 Autoharps, of which the following description, in connection with the accompanying drawings, is a specification, like letters on the drawings representing like parts.

Stringed musical instruments of the class 10 commonly known as "autoharps" consist, essentially, of a series of strings stretched upon a suitable bed or sounding-board and adapted, under the action of the finger or pick, to vibrate and produce musical tones 15 or chords, said chords being varied by means of pads mounted upon suitable carriers and adapted to be moved against and to damp or prevent vibration of such strings as are not necessary to produce the desired tones or 20 chords.

Prior to my invention, so far as I am aware, these muffling or damping pads have always been mounted upon swinging or vertically-movable bars ranged over and crossing the 25 strings, each bar having the proper number and arrangement of pads for a particular chord. Usually as many separate bars are required as there are chords to be produced, although in some instruments the pads are 30 made movable on their carriers. In any event, however, the range or capacity of the instrument is restricted to the number of carriers which can be crowded into a comparatively narrow space extending across the 35 strings, and in order to get as many bars as possible into such space said bars are frequently so crowded together and made so small as to render the instrument difficult of manipulation. To obviate these difficulties— 40 i. e., to increase the range of the instrument, yet simplify the construction and operation of the same—I have devised an instrument, forming the subject of this present application, in which the damping or muffling pads 45 are mounted upon a rotatable carrier, which also, if desired, may be made longitudinally movable, rotation and longitudinal movement of said carrier bringing different pads or sets of pads into contact with and to damp 50 various strings.

Suitable indicating characters or marks are preferably displayed upon the carrier to guide the musician in handling the instrument.

In the drawings, Figure 1 is a top or plan view of an instrument, illustrating one embodiment of my invention; Fig. 2, a cross-sectional detail on the dotted line xx , Fig. 1; Fig. 3, a detail looking at a portion of the under side of the carrier, showing the pads thereon; and Fig. 4, a detail showing one form 60 of guiding-strip.

In the particular embodiment of my invention shown in the drawings, A is a base or sounding-board of suitable shape and construction, the same holding the pins $a a$, between 65 which are strung the wires or strings $b b$.

C is one form of carrier, the same, as shown, being octagonal, or it may have any other desired number of sides or faces, or even cylindrical, and pivoted at its ends between 70 two arms $c c$, fast on the ends of a rod c' , mounted in the socket of the standards $d d$, erected on the base or sounding-board A. The standards $d d$, as shown, also carry a fixed rod d^2 , which serves as a track for the 75 roller or wheel e , mounted in a spring-arm e' on the pivot-rod c' of the carrier-frame. This spring-arm or spring e' acts upon the red d^2 to maintain the carrier C normally in its elevated full-line position, Fig. 2, but 80 yields, however, under pressure to permit said carrier to be depressed into its dotted position to damp the strings, as will be described.

In the embodiment of my invention here 85 shown I have applied to a plurality of adjacent faces of the octagonal carrier C a series of pads or damps $f f$, adapted to be pressed in contact with and to prevent vibration of certain of the strings b . The pads on the 90 several faces are arranged with intervening spaces or breaks f' to leave free to vibrate certain strings, the tones of which will produce the desired chords. The arrangement of pads on each face also is different to produce different chords, and the pads also on any one face are so arranged or set that if the carrier be slid along in its bearings into different positions, as indicated in dotted lines, Fig. 1, the pads on any one face will in the 95 100

different longitudinal positions of the carrier and without rotation of the latter produce different combinations of tones or chords.

The arrangement of pads may be varied as desired, so that rotation or sliding movement of the carrier, or both combined, will enable practically any desired chord or combination of tones to be obtained when the finger or pick is drawn across the strings.

- 10 Upon the faces of the carrier C opposite those faces on which the pads are arranged I have placed characters or figures to guide the musician in manipulating the instrument, the characters, as shown, being arranged over the open spaces or breaks f' between the pads on the opposite face—i. e., over the strings which are to be left free to vibrate. For example, on the top face of the carrier will be seen the figures "1," "3," and "5," repeated several times, indicating that when the carrier, with that particular face up, is depressed upon the strings, with the "1" over the string representing the keynote, the first, third, and fifth of the diatonic scale will sound. By rotating the carrier toward the top of the instrument and then depressing the same the second, fourth, fifth, and seventh will be sounded, and by rotating it in an opposite direction and depressing as before the first, fourth, and sixth will be sounded. By sliding the carrier along so as to bring the first, second, or other desired tone over the corresponding strings of the scales in different keys the same combinations in different keys
- 35 may be obtained.

In the instrument shown the strings are arranged to produce the chromatic scale, and to guide the operator I have arranged upon the base or sounding-board beneath the strings a strip s, on which is a representation of the keys of a piano, the strings or wires of the instrument passing directly over the corresponding keys on the strings.

My invention is not limited to the particular embodiment of the same herein shown, for it is evident the same may be varied without departing from the spirit and scope of my invention.

I claim—

- 50 1. In a stringed instrument, the combination with a base; and a series of strings stretched thereon, of a rotatable carrier traversing said strings, arranged to move toward and from said strings, and a plurality of damping-pads on said carrier and adapted to be brought into operative position by rotation thereof, substantially as described.

2. In a stringed instrument, the combination with a base, and a series of strings stretched thereon, of a rotatable carrier traversing said strings, a spring to normally raise said carrier out of contact with said strings, and a plurality of damping-pads on said carrier, substantially as described.

- 65 3. In a stringed instrument, the combination with a base, and a series of strings

stretched thereon; of a rotatable and longitudinally-movable carrier traversing said strings, arranged to move toward and from said strings and a plurality of damping-pads on said carrier, to operate, substantially as described.

4. In a stringed instrument, the combination with a base, and a series of strings stretched thereon, of a rotatable polygonal carrier, and supports therefor, a series of damping-pads on a plurality of the faces thereof, and indicating-characters on the corresponding opposite faces, substantially as described.

5. A stringed musical instrument provided with a sounding-board, a set of strings, and a rotatable multifaced carrier having a plurality of damping-pads arranged thereon in series on successive faces, adapted to be brought into operative contact with the strings, substantially as described.

6. A stringed musical instrument provided with a sounding-board, a set of strings, and a rotatable and vertically-movable and longitudinally-adjustable carrier having a plurality of damping-pads thereon, substantially as described.

7. A musical instrument provided with a sounding-board, a set of strings, and a rotatable multifaced carrier having a plurality of damping-pads thereon, arranged to cover three or more of said successive faces, and having intervening spaces therein, as desired, substantially as described.

8. A stringed musical instrument provided with a sounding-board, a set of strings, a fixed rod extending transversely thereof, a second rod pivoted to rotate parallel with and adjacent to said fixed rod in fixed bearings adjacent the ends of said fixed rod, fixed arms extending from either end of said pivoted rod, a carrier supported by the free ends of said arms and having a plurality of damping-pads arranged thereon, and a spring centrally fixed on said pivoted rod and arranged to engage said fixed rod whereby said carrier is normally raised from said strings, substantially as described.

9. A stringed musical instrument provided with a sounding-board, a set of strings, a fixed rod extending transversely thereof, a second rod pivoted to rotate parallel with and adjacent to said fixed rod in fixed bearings adjacent the ends of said fixed rod, said rod being also movable longitudinally in said bearings, fixed arms extending from either end of said pivoted rod, a carrier supported by the free ends of said arms and having a plurality of damping-pads arranged thereon, a spring centrally fixed on said pivoted rod, and arranged to engage said fixed rod, whereby said carrier is normally raised from said strings, and a friction-roller engaging said fixed rod and having bearings at either end respectively on said spring and in said pivoted rod, substantially as described.

10. A stringed musical instrument provided with a sounding-board, a set of strings and a rotatable carrier having a plurality of longitudinal series of damping-pads arranged thereon, adapted to be brought into operative contact with the strings, substantially as described.

In testimony whereof I have signed my name to this specification in the presence of two subscribing witnesses.

SIDNEY GRANT STUART.
